Louis Katz, New York, N. Y.

Application March 20, 1939, Serial No. 83,682

Term of patent 3½ years

To all whom it may concern:

Be it known that I, Louis Katz, a citizen of the United States, residing in New York city, in the county of New York and State of New York, have invented a new, original, and ornamental Design for a Dress Ensemble, of which the following is a specification, reference being had to the accompanying drawings, forming part thereof.

Figure 1 is a front view of a dress ensemble showing my design.

Figure 2 is the rear view thereof.

Figure 3 is a front view of the dress section of the ensemble as shown in Figure 1,

Figure 4 is the rear view thereof, and

Figure 5 is an enlarged fragmentary view of the dress ensemble showing the embroidery trim appearing thereon.

The characteristic feature of my design resides in the combination on the ensemble disclosed of the specific embroidered bands arranged on the bolero jacket and on the skirt and dress top, as shown.

I claim:

The ornamental design for a dress ensemble, substantially as shown and described.

LOUIS KATZ.
